[57] CLAIM

The ornamental design for corrugated metal clad dwelling, as shown and described.

DESCRIPTION

FIG. 1 is a front elevation of one preferred embodiment of a corrugated metal clad dwelling in accordance with my invention;

FIG. 2 is a rear elevation of the corrugated metal clad dwelling shown in FIG. 1;

FIG. 3 is a right side elevation of the corrugated metal clad dwelling shown in FIG. 1;

FIG. 4 is a left side elevation of the corrugated metal clad dwelling shown in FIG. 1; and

FIG. 5 is a top plan view of the corrugated metal clad dwelling shown in FIG. 1.

The bottom of the corrugated metal clad dwelling shown in FIG. 1 is unadorned.

FIG. 6 is a front elevation of second embodiment of a corrugated metal clad dwelling in accordance with my invention;

FIG. 7 is a rear elevation of the corrugated metal clad dwelling shown in FIG. 6;

FIG. 8 is a right side elevation of the corrugated metal clad dwelling shown in FIG. 6;

FIG. 9 is a left side elevation of the corrugated metal clad dwelling shown in FIG. 6; and,

FIG. 10 is a top plan view of the corrugated metal clad dwelling shown in FIG. 6.

The bottom of the corrugated metal clad dwelling shown in FIG. 6 is unadorned.
